UPPER SHAPING MACHINE

Eric A. Holmgren, Beverly, Mass., assignor to
 United Shoe Machinery Corporation, Flemington, N. J., a corporation of New Jersey

Application November 26, 1942, Serial No. 466,974

80 Claims. (Cl. 12—97)

This invention relates to upper-shaping machines and is herein illustrated in its application to machines for shaping prewelt uppers. It is to be understood, however, that the invention is not limited to machines which operate on prewelt uppers, the invention, in certain aspects thereof, being applicable to upper-shaping machines generally.

It is an object of the present invention to provide a machine for shaping prewelt uppers without the aid of lasts, thus effecting an economy in prewelt shoe manufacture and expediting the upper-shaping operation by obviating the handling of lasts and their insertion into the upper. It is a further object of the invention to perform the usual overwiping operation to position the welt for attachment to an outsole while the upper is so positioned on an inner form that it is under no tension either widthwise or lengthwise of the upper and, consequently, no resistance is offered to the overwiping operation and the welted margin is wiped in quickly and easily without exerting any strain against the welt-attaching seam.

With the above objects in view, the present invention in one aspect thereof comprises an upper-shaping machine having an upper-shaping expander, wiping means herein illustrated as a wiper plate, means for effecting relative movement of said expander and said wiper plate to wipe the bottom margin of an upper in over said expander, and means for actuating said expander to shape the overwiped upper. The illustrated expander comprises an inner upper-shaping plate over which the wiper plate wipes the bottom margin of the upper, and an inner upper-shaping mold which in the illustrated machine moves relatively to the upper-shaping plate to expand and shape the upper.

The illustrated inner plate is made bilaterally symmetrical in shape in order to adapt it to operate on both right and left uppers, the peripheral contour of the plate being such that it imparts a preliminary shape to the upper which closely approximates the final shape to be imparted to the upper, the final shaping being accomplished with ease in the sole-attaching operation. The illustrated inner upper-shaping mold is made somewhat smaller in girth than uppers in the run of sizes on which the particular mold is intended to operate, thus facilitating the positioning of the upper on the mold and permitting the overwiping operation to be performed with the upper free from strain or tension.

Features of the invention are to be recognized in means for actuating the upper-shaping mold,

said means effecting a relative movement of the mold and the inner upper-shaping plate heightwise of the upper to expand the upper, that is, to increase its girth, and means for effecting relative movement of the mold and said plate lengthwise of the upper to bulge the upper, that is, to extend it toewardly to increase the peripheral dimension of that portion of the upper on which the mold operates. To provide for length-

wise movement of the mold, said mold is movably mounted in a carrier and an actuator is provided for moving the mold longitudinally in said carrier. The heightwise movement of the mold is effected by an actuator which operates on the carrier to move it heightwise of the upper. In the illustrated machine, in accordance with a further feature of the invention, the heightwise and lengthwise movements of the mold occur substantially simultaneously, a common operating means herein illustrated as a hand lever being provided for simultaneously advancing said actuators.

In order to hold the bottom margin of an upper against displacement from its overwiped position on the inner upper-shaping plate during the operation of the mold, the illustrated machine, in accordance with a further feature of the invention, is provided with means herein illustrated as presser bars for causing the wiper to grip the margin of the upper against said plate upon the completion of the wiping operation. To facilitate the operation of the machine, a common actuator is provided for the operation of the wiper and the presser bars, said actuator being connected to the wiper by means including connections which, upon completion of the operation of the wiper, are rendered ineffective to advance the wiper further, while permitting the actuator to advance said presser bars relatively to the wiper to perform their appointed function.

In accordance with a further feature of the invention, the illustrated machine is provided with means for yieldingly supporting a prewelt upper by engagement within the welt crease, means herein illustrated as a welt-engaging member for locating the welted margin in a predetermined heightwise position, the upper being held in said predetermined position for the overwiping operation by the gripping action of the inner and outer forms. The illustrated welt-engaging member is constructed and arranged to engage the outsole-attaching surface of the welt and to bring the welted margin into a position of registration with the edge face of the inner upper-

shaping form to arrange the welted margin for the overwiping operation.

In accordance with a further feature of the invention, the welted margin of the upper after being positioned heightwise thereof by the locating means above described, is secured in such heightwise position by being gripped between the inner upper-shaping plate and means herein illustrated as a pair of complementally-shaped outer forms constructed and arranged to cooperate with said plate to grip the upper and hold it in its predetermined position. In the illustrated machine, the inner upper-shaping plate and the outer forms are so positioned heightwise of the upper relatively to said locating means that a uniform width of overwiping margin is provided.

After the overwiping margin has been wiped in over the inner upper-shaving plate and gripped against said plate by the operation of the presser bars on the wiper plate, the outer forms are retracted to provide clearance for the bulging operation of the mold. In the illustrated machine, the retraction of the outer forms is effected by means operated by the wiper actuator during the latter part of the advancement of the presser bars.

To insure a uniform wiping of the welted margin of a prewelt upper inwardly over the upper-shaping plate, the illustrated machine, in accordance with a further feature of the invention, is provided with means for conforming the welt to the peripheral contour of said plate to position the welted margin for the overwiping operation, said means being herein illustrated as a welt-conforming plate constructed and arranged to engage the outer edge face of the welt after the wiper plate has engaged the corners of the toe portion of the welted margin and brought the welt into sole-attaching position. The welt-engaging edge face of said welt-conforming plate is so constructed that when said plate is in its advanced or welt-conforming position, its welt-engaging edge face is uniformly spaced from the edge face of the inner upper-shaving plate. The illustrated welt-conforming plate is carried by the wiper plate and moves with the wiper into welt-engaging position in which position it is yieldingly held while the wiper advances relatively to said welt-conforming plate to complete its overwiping movement.

In the illustrated machine, a wiper actuator operates alternately to advance and to retract the wiper, means being provided for shifting the connections from the actuator to the wiper to effect a reversal of the wiper movement. The illustrated mechanism includes a pair of links which operate alternately at opposite ends of a rocker and means operating automatically upon the idle stroke of the actuator to shift said links relatively to the rocker.

These and other features of the invention will now be described with reference to the accompanying drawings and pointed out in the appended claims.

In the drawings,

Fig. 1 is a side elevation, partly broken away, illustrating a machine embodying the features of the present invention;

Fig. 2 is a front elevation of the head of the machine;

Fig. 3 is a central longitudinal section of the machine head, the section plane being indicated by the line III-III of Fig. 4;

Fig. 4 is a plan view illustrating the mecha-

nism for forming the toe portion of the upper;

Fig. 5 is a plan view illustrating in detail certain mechanism partially shown in Fig. 4;

Fig. 6 is a plan view illustrating the work-engaging portions of certain toe-forming parts at an intermediate stage in the operation of the machine;

Fig. 7 is a detail view in side elevation illustrating the mechanism for initially supporting and positioning the welted margin of the toe end of the upper, certain parts being broken away and the toe portion of a prewelt upper being shown partially in section;

Fig. 8 is a detail view, similar to Fig. 7, showing the upper gripped between the inner and outer forms;

Fig. 9 is a detail view, similar to Fig. 8, showing the wiper in an early stage of its advancement;

Fig. 10 is a side elevation, similar to Fig. 9, showing the wipers at the limit of their advancement;

Fig. 11 is a detail view, similar to Fig. 10, showing the mold in its upper-extending and bulging position;

Fig. 12 is a section taken on the line XIII-XII of Fig. 11; and

Fig. 13 is a detail view, partly in section, illustrating the mechanism connecting the wiper-actuating treadle to the wiper lever.

The illustrated machine is designed to operate on the uppers of prewelt shoes in the range of the smaller children's sizes, such shoes being characterized by a rather pronounced square toe having sharply curved corner portions which present a difficult problem in the handling of the welted margin in the upper-shaping operation. The machine illustrated in the drawings is particularly adapted to handle with ease said sharply curved portions of the upper and to arrange those portions of the welt for the subsequent shoe-making operations.

In the illustrated machine, the toe portion of a prewelt upper is initially supported in inverted position on the upturned end portion of a thin resilient plate 108 (Fig. 3) which supports the upper by the engagement of its upper edge within the welt crease. This plate is yieldingly mounted to permit the toe portion of the upper to be moved downwardly into a predetermined heightwise position by a member 36 which operates against the welt. This member positions the upper heightwise thereof in predetermined relation to an upper gripping means comprising a pair of forms 88 (Fig. 4), made of Bakelite or other suitable non-corrosive material, constructed and arranged to engage the outer surface of the toe portion of the upper along a line parallel to the welt seam and an inner form or plate 86 arranged to engage the inner surface of the upper at a position heightwise of the upper corresponding to the position of the outer forms, said inner form having an edge contour complementary to the contour defined by the outer forms in their upper-gripping position. The upper-positioning member so positions the welted margin with relation to the upper-gripping forms that it measures a uniform and predetermined width of upper margin, said margin extending upwardly from said forms in position to be wiped inwardly over the margin of the inner form by the operation of a wiper plate 126 (Fig. 3), preferably made of Bakelite, having a generally V-shaped wiping surface constructed and arranged to act against the sole-

attaching face of the welt. It will be understood that the upper-gripping members in addition to their functions of gripping the upper and supporting the welted margin during the wiping operation also establish a predetermined peripheral contour of the toe portion of the upper corresponding generally to the peripheral contour of an outsole suitable for attachment to the upper. The wiper plate is so constructed and arranged that its first points of contact with the welt are at the sharply curved portions at opposite sides of the toe portion of the upper. The engagement of the wiper with the sharply curved portions of the welt bends the welted margin inwardly over the margin of the inner upper-shaping plate and arranges the toe portion of the welt in a horizontal position in which the outer edge face of the welt registers with the welt-engaging edge face of a welt-conforming plate 138 (Fig. 6) which advances with the wiper and engages the welt immediately after the wiper has bent the welt into horizontal position, as shown in Fig. 6. That portion of the welt extending heelwardly from the toe end of the upper is held in horizontal position by the operator to receive the welt-conforming plate. The illustrated welt-conforming plate has a welt-engaging edge face which is so shaped that in the advanced position of said plate, said edge face is spaced uniformly from the edge face of the inner upper-gripping plate 86. The welt-conforming plate is positioned adjacent to the under surface of the wiper plate and advances with the wiper plate into welt-engaging position. By its engagement with the outer edge face of the welt, the welt-conforming plate determines the overwiped position of the welted margin and insures a uniform disposition of the welt with relation to the inner plate 86 over which the welted margin is wiped. The advancement of the welt-conforming plate is arrested by the welt itself, the extent of overwiping of the upper being determined by the width of upper margin projecting upwardly from the upper gripping forms. After the welt conforming plate is arrested, the wiper plate continues its advancement almost to the ball portion of the shoe and, in the course of this movement, presses the welted margin downwardly against the margin of the inner form. Upon completion of the advancement of the wiper plate downward pressure is applied thereto to cause it to grip the welted margin against the margin of the inner form and hold it against displacement from its overwiped position thereon during the subsequent upper-molding operation.

For performing the upper-molding operation, a suitably shaped form or mold 236 (Fig. 3), positioned adjacent to the under surface of the inner plate 86 moves downwardly to expand the upper heightwise thereof and toewards to create a well-defined bulge in the toe end of the upper. Prior to the movement of said mold, the outer upper-gripping forms 88 move away from the upper in order not to restrict the toewards movement of the mold.

In Fig. 2 there are illustrated two embodiments of the invention, one being the toe-molding machine hereinafter specifically described, and the other, which is mounted in the same machine head, being a machine for molding the heel portion of the upper. The heel-molding machine differs from the toe-molding machine only in that the outer forms extend vertically substantially the full height of the upper and

also in that the inner form does not have the upper-expanding and upper-bulging action of the toe-shaping mold member. In other respects, the functions and the mechanism of the heel end molding machine are substantially the same as in the toe-molding machine. Accordingly, the heel end molding machine is not hereinafter specifically described,—a specific description of the toe-molding machine being considered sufficient to enable persons skilled in the art to comprehend the construction and operation of both machines.

Referring now to Fig. 1, the illustrated toe-forming machine is mounted in a machine head 15 supported by a standard 22, the forward portion of the machine head having forwardly extending parallel vertical walls 24 between which the wiper and other operating parts are mounted. Parallel arms 26 extend forwardly from the walls 24 and provide the forward portions of a guideway in which the mechanism above-referred to is mounted. In the upper portions of the walls 24 are bearings for a cross-shaft 28 to which is secured a carrier or block 30 which carries those portions of the upper-forming mechanism operating within the toe portion of the upper. Mounted between inward extensions 32 (Fig. 2) of the upper portions of the walls 24 are parallel vertical arms 34 which carry at their lower ends 20 an upper-positioning plate 36 which acts against the welt and upper to position the upper heightwise thereof relatively to the operating mechanism (Fig. 7). As shown in Fig. 1, the arms 34 have vertical slots 38 through which the cross-shaft 28 extends, the engagement of said shaft with the parallel walls of the slot serving to determine the path of movement of said plate 36. The block 30 and the plate 36 are actuated by a treadle 40 fulcrumed at 42 in the base of the machine standard. For imparting the downward movement of the treadle to the plate 36 a link 44 extends upwardly from the treadle to an arm 45 of a three-armed lever, the arm 46 of which is connected by a link 48 to the rear end 45 of an arm 50 secured to a cross-shaft 52 journaled in vertical arms 53 (Fig. 7). Extending forwardly from the cross-shaft 52 are arms 55 (Fig. 2) pivoted at their forward ends to the upper end portions of the arms 34 which carry the plate 36. The plate 36 is normally held in retracted position by a spring 56 which acts on the arm 50. For swinging the block 30 and the upper-shaping mechanism mounted thereon from the position of said assembly illustrated in Fig. 1 downwardly and rearwardly into the toe portion of a supported upper, the arm 57 of the three-armed lever is pivotally connected to a vertical link 58, the upper portion of which has a pin-and-slot connection to an arm 60 secured to the shaft 28. To time the downward movement of the plate 36 to terminate just prior to the completion of the advancement of the block 30 the link 48 is slotted at 49 to provide a predetermined lost motion of the arm 46. A spring 62 connected to the arm 60 normally holds said upper-shaping assembly in its retracted position, illustrated in Fig. 1. Inasmuch as it is necessary to return the plate 36 to its retracted position at an early stage in the machine cycle to provide clearance for the operation of certain parts hereinafter described, means is provided for locking the block 30 and the upper-forming assembly mounted thereon in their advanced position, illustrated in Fig. 8, and after said assembly has been so locked the

treadle 40 is permitted to return to its elevated position while the spring 56 retracts the plate 36. The upward movement of the treadle will of course move the link 58 upwardly, the slot in said link being long enough to accommodate the up-stroke of the treadle. Referring to Fig. 8, the mechanism for locking the upper-forming assembly in its advanced position comprises a pawl 64 constructed and arranged for locking engagement with a segmental plate 66 secured to the right end of the shaft 28 and provided with a notch 68 which receives the downwardly extending tooth 70 of the pawl. In order to prevent the segmental plate 66 from swinging beyond the point of registration of the notch and the pawl, a segmental plate 72 (Fig. 3) is secured to the left end of the shaft 28 and arranged to register with a fixed stop member 74 which acts against lugs 76 and 78 on the segmental plate. The engagement of the lug 78 with the stop member arrests the advancement of the upper-forming assembly with the pawl 64 in registration with the notch 68 in the segmental plate 66. The engagement of the lug 76 with the stop member determines the retracted position of the upper-forming assembly illustrated in Fig. 3. Referring to Fig. 7, the plate 36 positions the toe portion of the upper heightwise thereof in the machine by engagement of its bottom surface 80 with the adjacent edge faces of the welt and upper of a prewelt upper such, for example, as the upper 82, partially illustrated in Fig. 7. The plate 36 also serves to bring the welted margin into registration with the upper-shaping forms hereinafter described, this function being performed by the engagement of a beveled surface 84 of the plate 36 with the welted margin of the upper during the downward movement of the plate, said beveled surface acting to bend the welted margin inwardly from its initial outspread position into its position illustrated in Fig. 7. It will be understood that the beveled surface 84 has a curvature complementary to the curvature desired for the toe portion of the welted margin of the upper at the intermediate station in the upper-shaping operation illustrated in Fig. 7. The plate 36 positions the welted margin at the toe portion of the upper at a uniform elevation above the inner upper-shaping plate 86, thus providing an overwiping margin of uniform and predetermined width. The plate 86 has the general peripheral contour of the forepart of a last bottom, but is made bilaterally symmetrical, as shown in Fig. 6, in order to permit its operation on both left and right shoes without adjustment. It will be understood that since the shoe in its final form is not symmetrical in shape at its toe portion, the upper must be further shaped, after it has been operated upon by the illustrated machine, but the further shaping required to put the upper into its final form is relatively slight and can be readily accomplished after the upper has been initially shaped in the present machine. Referring to Fig. 3, the plate 86 is secured to the forward surface of the block 30 by screws 90 which accurately locate the plate with relation to the outer forms 88. Referring to Fig. 4, the outer forms 88 are pivotally mounted on a carrier plate 92, upon the headed screws 94 positioned at the outer corner portions of said forms. In their rest position the outer forms 88 are arranged, as shown in Fig. 4, with their forward end portions abutting stop screws 96 carried by the plate 92. In this position the separation of the forward

portions of the outer forms is somewhat greater than the width of the corresponding portion of the plate 86 and consequently said plate, during its advancement into the upper will first grip the central portion of the toe end of the upper against the end portions of the outer forms 88 and further advancement of the plate 86 thereafter will by pressure of its toe end against the outer forms swing the forward portions of the forms inwardly to cause the upper to be gripped between the plate 86 and the outer forms along the entire length of their gripping surfaces. As shown in Figs. 8 and 12, the work-engaging portions of the outer forms 88 extend upwardly from each form, the outer surface of said upward extension being beveled to provide a narrow upper edge portion which facilitates the initial positioning of the welted margin of the upper upon said outer form. The carrier plate 92 is slidably mounted in a suitable guideway provided by the walls 24 (Fig. 2) and the arms 26 and inward extensions 93 which underlie and support said carrier plate. The carrier plate is urged forwardly in its guideway by a spring 98 (Fig. 8) one end of which is secured to a bracket 100 and the other end of which is anchored to the machine frame. When the machine is at rest, the carrier plate 92 is positioned by the engagement of a stop screw 102 in the bracket 100 with a fixed abutment 104. The upper-engaging plate 86 forces the carrier plate rearwardly slightly into its position illustrated in Fig. 8 and causes the spring 98 to exert upper-gripping pressure against the outer forms 88. The gripping pressure thus exerted is sufficient to prevent any heightwise displacement of the upper by the action of the wiper plate.

In order to assist the operator in positioning the welted margin at the toe end of the upper at an elevation such that it will be engaged and moved downwardly by the operation of the plate 36, a resilient toe-supporting plate 108 (Fig. 3) is supported by the carrier plate 92 and is so positioned that its upturned end portion resting on the rounded edges of the outer forms 88 supports the toe portion of the upper by engagement within the welt crease (Fig. 7). The rear portion of the plate 108 is fixed in a block 110 (Fig. 5) which is swivelled on a plate 112 pivotally mounted on a headed screw 114 projecting upwardly from the carrier plate 92, the plate 108 being urged forwardly into its upper-supporting position by a spring 116 operating on the plate 112. It will be understood that during the downward movement of the plate 36, the plate 108 is forced downwardly and rearwardly upon the beveled surfaces of the outer forms 88 against the tension of said spring 116. In order to withdraw the upturned end portion of the plate 108 into a position in which it will not obstruct the operation of the wiper and other operating parts, the plate 112 is swung in a clockwise direction, as seen in Fig. 5, by the operation of a pin 118 extending downwardly from the welt-conforming plate, hereinafter referred to, against an extension 120 of the plate 112 during the forward movement of said welt-conforming plate. To facilitate the vertical movement of the work-engaging end portion of the plate 108, the adjacent end portions of the outer forms 88 are recessed to provide continuous beveled surfaces 122 on which said plate may move, the end portion of said plate being held against widthwise movement between shoulders 124 (Fig. 5) which terminate the beveled surfaces 122.

For wiping the welted margin inwardly over the margin of the inner plate 86, the illustrated machine is provided with a wiper plate 126 (Fig. 3) removably secured by headed screws 128 in a recess in the bottom of a wiper carrier 130. Referring to Fig. 9, the wiper carrier moves longitudinally over two pairs of rolls 132 and a third pair of rolls 134 slightly offset upwardly with relation to the rolls 132, all of said rolls being mounted to turn on headed pins 135 (Fig. 4) extending through the walls 24. The rolls 134 cause the wiper carrier to advance in a downwardly inclined direction which enables the wiper 126 more effectively to bend the sharply curved corner portions at the toe end of the welted margin in over the margin of the plate 86. After the wiper has overwiped said corner portions, the roll-engaging plates 137 on the under side of the wiper carrier 130 ride off the rolls 134 and the wiper continues its advancement in a generally horizontal position. As the wiper proceeds, the welt 136, being slightly higher than the rolls 132 causes the plates 137 to rise slightly above said rolls and the wiper is thereafter positioned solely by its engagement with the welt. The connections between the wiper carrier and its operating means, hereinafter described, afford a limited freedom of movement of the wiper assembly about axes extending both lengthwise and widthwise of the supported upper to permit the wiper to be so positioned by its contact with the welt that it presses uniformly against the opposite side portions and the end portion of the welted margin of the upper. It will also be understood that since the wiper is supported solely by the welt during the greater part of its wiping movement, downward pressure applied to the wiper by means hereinafter described is effective to press the welted margin of the upper against the plate 86.

For conforming the welt 136 to the peripheral contour of the upper-engaging plate 86, as shown in Fig. 6, the illustrated machine is provided with a plate 138 the forward portion of which is recessed to provide an edge face 140 which, in the operative position of said plate illustrated in Fig. 6, is uniformly spaced from the edge face 141 of the plate 86. The welt-conforming plate is positioned adjacent to the bottom surface of the wiper carrier 130 (Fig. 3) and advances with the wiper carrier in the position relative to said carrier illustrated in Fig. 6. The welt-conforming plate 138 engages the outer edge face of the welt after the wiper has overwiped the welted margin at the corners of the toe end of the upper, Fig. 6 illustrating the relative position of the welt, the wiper and the welt-conforming plate at the instant the welt-conforming plate comes into contact with the welt. As the wiper continues to advance from this position, the welt-conforming plate 138 remains at rest and is held in welt-engaging position by the tension of a light spring hereinafter identified. Referring to Figs. 3, 4, and 6, the illustrated welt-conforming plate is carried by headed screws 142 extending upwardly into the wiper carrier, said screws being positioned within recesses 144 at opposite sides of the welt-conforming plate and the heads of said screws extending in under rabbeted portions 145 at opposite sides of the plate and providing means for supporting the plate and positioning it widthwise thereof. Extending rearwardly from the plate 138 is an arm 146 (Fig. 3) having a downwardly extending pin 148 which carries the rear end of a tension spring 150 the forward

end of which is anchored to the machine head. The spring 150 normally holds the wiper carrier and the welt-conforming plate in their relative position illustrated in Fig. 6 with the screws 142 in engagement with the rear end walls of the recesses 144.

For applying a relatively light downward pressure to the wiper during its overwiping movement, a pair of headed pins 168 are slidably mounted in vertical bores in the extensions 32 (Fig. 2) of the walls 24 and are pressed downwardly against rails 127 on the wiper carrier 130 by springs 170 (Fig. 3) surrounding the lower portions of said pins and mounted in counterbores in said extensions 32. When the wipers are retracted, the pins 168 are so positioned vertically by stop nuts 172 at their upper end portions that during the advancement of the wiper the headed ends of said pins are engaged and lifted by beveled end portions of said rails 127. For pressing the wiper in its advanced position downwardly against the welt to hold the overwiper margin against displacement on the plate 86, parallel presser bars 152 (Figs. 3 and 4) are slidably mounted in longitudinal grooves in the wiper carrier 130 and are held in said grooves by headed screws 154 extending through slots 156 in the presser bars. After the wiper comes to rest at the limit of its advancement, the presser bars 152 continue to advance into their position illustrated in Fig. 10 in which position beveled surfaces 158 at the forward end portions of the presser bars have engaged rolls 160 which yieldingly press the forward portions of said bars downwardly against the opposite side portions of the wiper carrier. As shown in Fig. 2, the rolls 160 are mounted at opposite ends of a cross-shaft 162, being positioned adjacent to the opposite sides of the block 30. As shown in Fig. 4, the shaft 162 is mounted in slots 164 in the block 30 and is yieldingly urged downwardly by a spring 166 mounted in a bore in said block and held under compression by a headless screw 167. The shaft 162 is free to rock about the lower end of the spring 166 in order to enable the rolls 160 to apply uniform pressure to opposite sides of the wiper regardless of variations in thickness of the welted margin at opposite sides of the upper. The downward pressure thus imparted to the wiper causes the wiper to grip the welted margin of the upper firmly against the margin of the plate 86 and to hold the welted margin against displacement during the subsequent upper-expanding and bulging operations. In order to insure a positive gripping of the welted margin against the plate 86 by the downward pressure of the wiper the edge portion of the plate 86 is provided with a small upwardly extending bead 174 which is pressed into the inner surface of the upper when the final pressure is applied to the wiper, as shown in Figs. 3 and 10.

For actuating the wiper 126 together with the welt-conforming plate 138 and the wiper presser bars 152, a treadle 176 (Fig. 1) is pivotally mounted in the base of the machine and connected by mechanism, now to be described, to an arm 178 fixed to a shaft 180 in the machine head and pivotally connected to the rearmost of a pair of toggle links 182 184 (Fig. 3) constructed and arranged to connect the upper end of the arm 178 to the rear portion of the wiper carrier 130. The treadle operates through mechanism so constructed and arranged that downward movement thereof alternately advances and retracts the wiper and associated parts. This

mechanism comprises a crossarm 186 (Fig. 13) fixed to the shaft 180 and provided at its opposite ends with pins 188 and 190 constructed and arranged to be engaged alternately by hooks 192 and 194 at the upper ends of links 196 pivoted at their lower ends to a pin 197 in the treadle 176. The hooks 192 and 194 are held uniformly spaced from each other by a link 198 which is of such a length that the space between the hooks is slightly less than the space between the pins 188 and 190 on the crossarm 186. Thus, when the hook 192 is acting on the pin 188 to swing the arm 186 in a counterclockwise direction, as seen in Fig. 13, the pin 190 moves upwardly without engaging the hook 194 which in this case is inoperative. In order that the next operation of the treadle 176 may swing the crossarm 186 in a clockwise direction, mechanism is provided for automatically shifting the interconnected hooks 192 and 194 so that the hook 194 will engage the pin 190. This mechanism comprises a bell-crank lever 200 freely mounted at its elbow on the shaft 180 and provided at its lower end with a wedge-shaped stop member 202 which engages alternately pins 204 and 205 projecting from the lower portions of the hooks. The pin-engaging edge faces 207 of the stop member 202 are arranged at such an angle to the downwardly extending arm of the bell-crank lever 200 that in their respective pin-engaging positions they extend substantially vertically and, consequently, the bell-crank lever receives no appreciable turning movement from the pins 204 and 205 during the downward movement of the hooks 192 and 194. It will be understood that the length of the pin-engaging surfaces 207 corresponds generally to the relative vertical movement of the bell-crank lever and the hooks. For causing the bell-crank lever to swing with the crossarm 186, a pair of pins 206 and 208 are mounted in longitudinal alignment with each other in bearings in a head 210 at the end of the short arm of the bell-crank lever 200 and arranged to engage an extension of the pin 190 at the right end of the crossarm 186. The heads of the pins 206 and 208 are connected together by a tension spring 212 which normally holds the horizontal arm of the bell-crank lever in registration with the arm 186. As the treadle is operated to swing the crossarm 186 in a counterclockwise direction, the stop member 202 on the bell-crank lever swings to the right as seen in Fig. 13 until it is arrested by engagement with the pin 205 on the hook 194. This occurs at an intermediate stage in the advancement of the arm 178. During the continued operation of said arm, the crossarm 186 imparts upward movement to the pin 206 against the tension of the spring 212. This continues until a stop screw 213 in the crossarm engages a fixed abutment 215 to arrest the advancement of the arm 178. In this position the arm 178 is yieldingly held against return movement by a pair of detents, one of which is illustrated in Fig. 3 and identified by the numeral 214. The detent 214 is fulcrumed at 216 in the machine head and arranged to engage an extension of a crosspin 220 which connects the upper portion of the arm 178 to the toggle link 184, a light spring 218 serving to urge the detent downwardly into operating position. The detent is extended horizontally to take in the full range of movement of the crosspin 220 with the arm 178 and is provided at opposite ends with recesses which terminate in beveled surfaces 222 which engage the crosspin 220 and yieldingly

hold the arm 178 in its extreme positions. The inclination of the beveled surfaces 222 is such that the detents do not appreciably hinder the operation of the arm 178 by the treadle 176 but the downward pressure of the detents is sufficient to hold the arm stationary in its extreme positions. It will be understood that the construction and operation of that detent which is not shown in Fig. 3 is the same as the construction and operation of the illustrated detent 214. While the arm 178 is yieldingly held in its advanced position by said detents, the treadle is permitted to return to its elevated position illustrated in Fig. 1. At the beginning of the upward movement of the treadle, the hook 192 is lifted out of engagement with the pin 188 whereupon the spring 212 swings the bell-crank lever 200 in a counterclockwise direction, as seen in Fig. 13, thus transferring the interconnected hooks to the right into a position in which the flat surface 223 of the hook 194 engages the pin 190. As the treadle continues its upward movement, the surface 223 moves upwardly with relation to the pin 190 and just before the treadle comes to the limit of its upward movement, said surface passes by the pin 190 and thereupon the spring 212 swings the hooks farther to the right bringing the surface 225 of the hook 194 into contact with the pin 190 and positioning the hook 194 to engage said pin upon the next succeeding operation of the treadle and to swing the bell-crank lever together with the arm 178 in a clockwise direction, as seen in Fig. 13, to retract the wiper and its associated parts. It will be understood that during the latter part of such downward movement of the treadle, the lower pin 208 is moved downwardly against the tension of the spring 212 and during the next succeeding upward movement of the treadle, the spring 212 acting through the bell-crank lever 200 returns the interconnected links to their position illustrated in Fig. 13 in which the hook 192 registers with the pin 188. The momentum of the bell-crank lever tends to carry it somewhat beyond its normal rest position in which the pin 190 is located centrally with relation to the head 210, as shown in Fig. 13, but the detents, acting on the crosspin 220, prevent the momentum of the bell-crank lever from displacing the arm 178 from its extreme positions. The arm 178 is connected to the wiper carrier 130 by the toggle links 182 and 184 above-referred to and is connected to the presser bars 152 by parallel links 224 (Fig. 4) carried by the crosspin 220 and pivotally mounted in the rear end portions of said presser bars. During the advancement of the wiper, the toggle links are held in their straightened or horizontal position illustrated in Fig. 3 by a spring 226 which acts against a pin 228 extending rearwardly from the link 184, the straightened position of the toggle links being determined by engagement of a rearward extension 230 of the toggle link 182 with a stop screw 232 in the link 184. The advancement of the wiper is arrested by the engagement of an upward extension 234 of the link 182 with a stop screw 235 in a bridge 237 connecting opposite side walls of the machine head but the advancement of the arm 178 continues as the toggle breaks to permit the presser bars 152 to be advanced relatively to the wiper as above described. It will be understood that during the return movement of the arm 178, the presser bars 152 move rearwardly relatively to the wiper as the toggle links return to their straightened position and thereafter the presser bars and the wiper

are retracted in unison to their rest positions. Thus, the pressure of the presser bars 152 against the wiper is released before the wiper is retracted.

For expanding and bulging the toe portion of the overwiped upper, an inner form or mold 236 (Fig. 3) is mounted on a carrier 238 having an upwardly extending stem 240 slidably mounted in a bore in the block 30. The illustrated mold has the general shape of the toe portion of a last and is shaped symmetrically in order that it may operate alternatively on right and left uppers. The girth dimension of the illustrated mold, that is, the measure widthwise around the mold of its upper-engaging surface, is substantially less than the inside girth dimension of uppers in the run of sizes to be operated upon by said mold to the end that the upper may be loosely positioned on the inner upper-shaping plate 86 and the mold during the overwiping operation, thus permitting that operation to be performed with the upper entirely free from strain or tension. As shown in Fig. 12, the carrier 238 is generally T-shaped in cross section and the mold 236 has a complementary T-shaped recess extending longitudinally thereof and permitting a limited sliding movement of the mold on the carrier. The mold is normally held in its retracted position on the carrier as shown in Fig. 3 by a spring 242 mounted in a longitudinal groove in the central portion of the base of the carrier, one end of the spring being connected to a pin 244 projecting from the mold into said groove and the other end being connected to a pin 246 projecting from the base of the carrier into said groove. The mold is normally held updrawn against the bottom face of the plate 86 by a spring 248 surrounding the upper portion of the stem 240 and confined between a washer 250 on the stem and the upper surface of the block 30. For imparting downward movement to the mold 236 to expand the toe portion of the upper heightwise thereof, a bent hand lever 252 is mounted on a cross-shaft 254 journaled in ears 256 extending upwardly from the machine head. The hand lever is connected by a link 258 to the rear portion of a lever 260, the forward portion of the link 258 being pivotally mounted on a pin 284 which is extended to provide a stop for the forward movement of the hand lever. The lever 260 carries at its forward end a screw 262 having a flat head 264 arranged to engage the upper end of the stem 240 when the block 30 is in its downwardly swung position illustrated in Fig. 10. The lever 260 has a downward extension 266 which is bored to receive the shaft 52 on which the lever is freely mounted. In order that the extent of downward movement of the mold 236 may be measured in accordance with the size of the upper to be operated upon, the screw 262 is provided with a headed cap 268 which may be turned to adjust the screw in the lever 260, and the lower portion of the cap is provided with an edged flange 270 which registers with a suitable scale 272 (Fig. 2) which indicates the adjustment of the screw in terms of shoe sizes. The hand lever 252 also operates a bent presser lever 274 (Fig. 3) mounted on the cross-shaft 254 and arranged to apply downward pressure to the wiper carrier 130 to grip the wiper against the toe end of the welted margin of the upper. The lever 274 has pivotally mounted at its upper end a block 276 which is bored to slide on a rod 278, the forward end of which is pivotally mounted in the rear portion of the lever 260. The block 276 is normally posi-

tioned lengthwise of the rod 278 between a spring 280 and a nut 282. Upon completion of the operation of the mold 236 and the presser lever 274 by the hand lever 252, the parts are arranged 5 in their relative position illustrated in Fig. 11. It will be seen that in this position of the parts, the lever 252 and the link 258 are so disposed that the compression of the spring 280 acts to maintain this position of the parts, since the pivotal 10 connection of the hand lever to the link 258 has passed slightly beyond its dead center position and come to rest with the lower portion of the lever and the link bent downwardly slightly with the hand lever held against the pin 284 on which the link 258 is pivoted.

In order that the outer forms 88 may be retracted to provide clearance for the longitudinal movement of the mold 236 in the upper-bulging operation, means is provided for retracting said 15 outer forms as the presser bars 152 complete their forward movement. To this end a bell-crank lever 286 (Figs. 1 and 10) is fulcrumed at 288 in the machine head, the lower portion of said lever having a forward extension 290 from which a pin 292 projects laterally for engagement with the bracket 100 on the carrier plate 92. The bell-crank lever 286 is swung in a counterclockwise direction, as seen in Fig. 10, during the latter part 20 of the forward movement of the arm 178 when a roll 294 carried by said arm engages a cam surface 296 on the under side of the horizontal portion of the bell-crank lever.

The mold 236 is forced rearwardly to perform the upper-bulging operation simultaneously with the downward or upper-expanding movement. For imparting such rearward movement to the mold, a lever 298 (Fig. 3) is mounted on a cross-pin 300 extending through lugs 302 on the block 30. At the lower end of the lever 298 a screw 304 is arranged to engage the flat forward surface of the mold 236. The lever 298 is normally held retracted by a torsion spring 306 (Fig. 2) surrounding the pin 300 and arranged to operate against a lateral extension 308 of the lever 298. 35 The lever 298 is actuated by the hand lever 252 through a thrust bar 310 (Figs. 1 and 11) fulcrumed at 312 on the lever 260. At its forward end, the thrust bar 310 is provided with a shoulder 314 which engages a pin 316 in an upwardly extending arm 318 of the lever 298. When said lever is in its rest position illustrated in Fig. 1, it is positioned by the engagement of the upwardly extending arm 318 with a pin 320 on the thrust bar 310. While the extent of movement of the 40 thrust bar is fixed, it will be understood that the extent of rearward movement of the mold 236 may be altered as desired by adjusting the screw 304 in the lever 298. Upon completion of the upper-expanding and bulging movement of the mold 236, the spring 280 (Fig. 3) acting on the link 258 and the hand lever 252 will yieldingly retain the mold in its advanced position.

In order to cause the upper to retain the shape imparted to it by the illustrated machine, the operating parts are heated by an electrically operated unit 322 (Fig. 2) mounted in the machine head.

The heel-molding machine, illustrated in Fig. 2, is mounted in an extension of the machine head 20 and so positioned that the operator may readily transfer the upper from one machine to the other to complete the preshaping of the upper preparatory to the sole-attaching operation. The illustrated heel-molding machine is similar in construction and operation to the toe-molding

machine above described except that the upper-expanding and bulging operations are not present in the heel-molding machine. Very briefly described, the heel-molding machine comprises an inner heel form or block 324 which forms the heel portion of the upper against a pair of complementally shaped outer heel molds 326. For wiping the welted margin over the top of the heel block 324 a heel wiper 328 is mounted in a carrier 330. For applying downward pressure to the wiper to flatten out the welt, a pair of presser bars 332 are mounted for sliding movement lengthwise of the upper in guideways in the wiper carrier.

In the operation of the toe-molding machine an inverted prewelt upper is mounted on the toe-supporting plate 108, the upper being held in a horizontal position by the operator who grips the opposite side portions of the welted margin with his two hands and holds those portions of the welt in a substantially horizontal position widthwise thereof in order to facilitate the operation of the wiper. After so positioning the upper, the operator depresses the treadle 40 to bring the upper-positioning plate 36 against the welted margin of the toe portion of the upper to locate said welted margin vertically and to cause it to register with the upper edge of the outer forms 88. The depression of the treadle 40 operates to bring the plate 86 into gripping engagement with the inner surface of the upper after the plate 36 has positioned the welted margin as above described. The treadle 40 is then permitted to return to its elevated position retracting the upper-positioning plate 36 but leaving the plate 86 in gripping engagement with the upper as shown in Fig. 8 in which position it is locked by the pawl 64. The operator now depresses the treadle 176 simultaneously advancing the wiper plate 126, the welt-conforming plate 138 and the presser bars 152. In the course of the advancement of these parts, the wiper first overwipes the corners of the toe portion of the upper, as shown in Fig. 6, bringing the toe portion of the welt into a horizontal plane and positioning the outer edge face of the welt to register with the welt-conforming plate which engages the welt immediately after it has been so positioned. The welt-conforming plate positions the welt uniformly widthwise thereof with relation to the plate 86 so that a uniform width of the welted margin is wiped inwardly over the plate 86. The advancement of the welt-conforming plate is arrested by its engagement with the welt and the wiper continues its advancement while wiping pressure is imparted thereto by the operation of the spring-pressed pins 168 (Fig. 9) against the rails 127. Upon completion of the wiping movement of the wiper plate 126, the toggle links 182 and 184 swing downwardly permitting the presser bars 152 to continue their advancement until their beveled ends engage the rolls 160 (Fig. 10) to apply gripping pressure to the wiper plate. The treadle 176 is then permitted to return to its elevated position whereupon the operator swings the hand lever 252 forwardly to perform the upper-expanding and bulging operations. Preferably, the upper is permitted to remain in the machine with the operating parts in their advanced positions, as shown in Fig. 11, in order that the upper may set to the shape imparted thereto by the machine. While the upper is setting in the toe-molding machine, the operator molds the heel portion of another upper in the heel-molding machine above described and while said up-

per is setting in the heel-molding machine, the first-mentioned upper is removed from the toe-molding machine and another upper is mounted therein. In retracting the operating parts of the toe-molding machine, the mold 236 is retracted forwardly and upwardly into its position illustrated in Fig. 10 by rearward movement of the hand lever 252 whereupon the treadle 176 is again depressed to retract the wiper plate and its associate parts. The pawl 64 is then withdrawn from the notch 68 in the plate 66 by the operation of a hand lever 334 (Fig. 8) secured to said pawl and the spring 62 (Fig. 1) swings the arm 60 downwardly returning the block 30 and the parts carried thereby to their rest position illustrated in Fig. 1.

Having thus described my invention, what I claim as new and desire to secure by Letters Patent of the United States is:

2. In an upper-shaping machine, an upper-shaping expander, wiping means, means for effecting relative movement of the expander and said wiping means to wipe the bottom margin of an upper in over said expander, and means for actuating said expander to shape the overwiped upper.
3. In an upper-shaping machine, wiping means, and an inner form over which the margin of the upper is wiped by said wiping means, said inner form being constructed and arranged to be positioned loosely within the upper thus permitting the overwiping operation to be performed with the upper entirely free from strain or tension.
4. In an upper-shaping machine, toe shaping means comprising a wiper member and an inner toe form over which said wiper member wipes the margin of an upper, said form being substantially smaller in girth during the wiping operation than the inside girth dimension of the toe portion of the upper.
5. In an upper-shaping machine, an inner upper-shaping plate, an inner upper-shaping mold positioned adjacent to said plate, and wiping means for wiping the margin of an upper in over said upper-shaping plate, said mold being constructed to be positioned freely within the upper during the overwiping operation.
6. In an upper-shaping machine, an inner upper-shaping plate, an inner upper-shaping mold, and a wiper member for wiping the bottom margin of an upper in over said plate, the combined girth measure of the plate and the mold being substantially less, during the overwiping operation, than the inside girth dimension of the upper.
7. In an upper-shaping machine, an upper expander so constructed and arranged that in its contracted condition its girth measure is less than the inside girth dimension of an upper supported in the machine, and means for wiping the bottom margin of the upper in over the contracted expander.
8. In an upper-shaping machine, means for supporting an upper, an expander so constructed and arranged that upon insertion into the supported upper in contracted condition it fits freely within the upper, and a wiper member for wiping the bottom margin of the upper in over said expander.
9. In an upper-shaping machine, an inner upper-shaping plate, an inner upper-shaping mold, wiping means, means for effecting relative movement of said inner plate and said wiping means to wipe the bottom margin of an upper

in over said plate, and means for effecting relative movement of said plate and said mold to shape the upper.

9. In an upper-shaping machine, an inner upper-shaping plate, an inner upper-shaping mold, a wiper member, means for effecting relative movement of the inner plate and the wiper member to wipe the bottom margin of an upper in over said plate, and means for effecting relative movement of said plate and said mold heightwise of the upper to expand the upper.

10. In an upper-shaping machine, an inner upper-shaping plate, an inner upper-shaping mold, a wiper member, means for effecting relative movement of the inner plate and the wiper member to wipe the bottom margin of an upper in over said plate, means for effecting relative movement of said plate and said mold heightwise of the upper to expand the upper, and means for effecting relative movement of said plate and said mold lengthwise of the upper to bulge the upper.

11. In an upper-shaping machine, an inner upper-shaping plate, an inner upper-shaping mold, a wiper member, means for effecting relative movement of said inner plate and said wiper member to wipe the bottom margin of an upper in over said plate, and means for effecting relative movement of said plate and said mold heightwise of the upper with a component of movement lengthwise of the upper.

12. In an upper-shaping machine, a plate having the general peripheral contour of a toe portion of a last bottom, an inner mold having the general shape of the forepart of a last, a wiper member, means for effecting relative movement of said plate and said member to wipe the bottom margin of the toe portion of an upper in over said plate, and means for effecting relative movement of said plate and said mold to expand the toe portion of the upper.

13. In an upper-shaping machine, a plate having the general peripheral contour of a toe portion of a last bottom, an inner mold having the general shape of the forepart of a last, a wiper member, means for effecting relative movement of said plate and said member to wipe the bottom margin of the toe portion of an upper in over said plate, and means for effecting relative movement of said plate and said mold lengthwise of the upper to bulge the toe portion of the upper.

14. In an upper-shaping machine, a plate having the general peripheral contour of a toe portion of a last bottom, an inner mold having the general shape of the forepart of a last, a wiper member, means for effecting relative movement of said plate and said member to wipe the bottom margin of the toe portion of an upper in over said plate, means for effecting relative movement of said plate and said mold heightwise of the upper to expand the toe portion of the upper, and means for effecting relative movement of said plate and said mold lengthwise of the upper to create a bulge therein.

15. In an upper-shaping machine, an inner plate having the general peripheral contour of an end portion of a last bottom, an inner form, a wiper member, means for effecting relative movement of said plate and said member to wipe the bottom margin of an upper inwardly over said plate, means for causing said member and said plate to grip the overwiped margin, and means for effecting relative movement of said plate and said mold to expand the upper.

16. In an upper-shaping machine, a plate hav-

ing the general peripheral contour of an end portion of a last bottom, a mold having the general shape of an end portion of a last, a wiper member, means for effecting relative movement of said member and said plate to wipe the bottom margin of an upper in over said plate, a presser for actuating said member to grip the overwiped margin against said plate, and means for effecting relative movement of said plate and said mold to expand the upper.

17. In an upper-shaping machine, means constructed and arranged to engage the bottom edge of an upper in the machine and to position the upper heightwise thereof with relation to the operating instrumentalities, an inner upper-shaping plate, an inner upper-shaping mold, means for moving said plate and said mold into the supported upper, a wiper member, means for effecting relative movement of inner plate and said wiper member to wipe the bottom margin of the upper in over said plate, and means for effecting relative movement of said plate and said mold to shape the upper.

18. In a machine for shaping prewelt uppers, means for yieldingly supporting an inverted prewelt upper by engagement within the welt crease, means constructed and arranged to engage the welted margin of the upper and to move the upper downwardly into a predetermined heightwise position, means including an inner upper-shaping plate for gripping the upper and holding it in said heightwise position, and a wiper member for wiping the welted margin in over said plate.

19. In a machine for shaping prewelt uppers, means for yieldingly supporting an inverted prewelt upper by engagement within the welt crease, means constructed and arranged to engage the welted margin of the upper and to move the upper downwardly into a predetermined heightwise position, means including an inner upper-shaping plate for gripping the upper and holding it in said heightwise position, and a wiper member constructed and arranged to engage the sole-attaching face of the welt and to wipe the welted margin in over said plate.

20. In a machine for shaping prewelt uppers, an inner upper-shaping plate, a wiper member, means for effecting relative movement of said inner plate and said wiper member to wipe the bottom margin of an upper in over said plate, and means for conforming the welt to the peripheral contour of said plate to position the welted margin for the wiping operation.

21. In a machine for shaping prewelt uppers, an inner form constructed and arranged to receive the welted margin of the toe portion of an upper in overwiped position, a toe wiper constructed and arranged to operate against the sole-attaching face of the welt, means acting against the wiper to cause it to grip the overwiped margin against the inner form, and an inner mold operable to shape the toe portion of the overwiped upper.

22. In a machine for shaping prewelt uppers, an inner form constructed and arranged to receive the welted margin of the toe portion of an upper in overwiped position, a toe wiper constructed and arranged to operate against the sole-attaching face of the welt, means acting against the wiper to cause it to grip the overwiped margin against the inner form, and an inner toe-shaped mold movable heightwise of the supported upper to expand its toe portion.

23. In a machine for shaping prewelt uppers,

an inner form constructed and arranged to receive the welted margin of the toe portion of an upper in overwiped position, a toe wiper constructed and arranged to operate against the sole-attaching face of the welt, means acting against the wiper to cause it to grip the overwiped margin against the inner form, an inner toe-shaped mold movable heightwise of the supported upper to expand its toe portion and movable longitudinally of the upper to create a bulge therein.

24. In a machine for shaping prewelt uppers, an inner form constructed and arranged to receive the welted margin of the toe portion of an upper in overwiped position, a toe wiper constructed and arranged to operate against the sole-attaching face of the welt, and means for measuring a predetermined width of overwiping margin.

25. In an upper-shaping machine, an upper-shaping expander comprising an inner upper-shaping plate upon which an upper is gripped for the expanding operation, and an upper-shaping mold positioned adjacent to said plate, the plate and the mold being relatively movable to expand the upper.

26. In an upper-shaping machine, an upper-shaping expander comprising an inner upper-shaping plate upon which the bottom margin of an upper is gripped for the expanding operation, and an upper-shaping mold positioned adjacent to said plate, said mold and said plate being relatively movable both heightwise and lengthwise of the supported upper to shape the forepart of the upper.

27. In an upper-shaping machine, an upper-shaping expander comprising an inner upper-shaping plate, a member on which the plate is mounted, and an upper-shaping mold supported by said member and movable heightwise of a supported upper relatively to said plate.

28. In an upper-shaping machine, an upper-shaping expander comprising an inner upper-shaping plate, a block on which said plate is mounted, an upper-shaping mold, and a carrier on which said mold is mounted for movement lengthwise of a supported upper, said carrier being mounted in said block for movement heightwise of the upper.

29. In an upper-shaping machine, an upper-shaping expander comprising a symmetrically shaped inner upper-shaping plate and an upper-shaping mold positioned adjacent to said plate, said plate and said mold being constructed and arranged for relative movement to expand an upper mounted thereon.

30. In an upper-shaping machine, an upper-shaping expander comprising a symmetrically shaped inner upper-shaping plate and a symmetrically shaped upper-shaping mold positioned adjacent to said plate, said plate and said mold being relatively movable to expand an upper mounted thereon.

31. In a machine for shaping prewelt uppers, means for yieldingly supporting a prewelt upper by engagement within the welt crease, means for locating the upper in a predetermined heightwise position comprising a member constructed and arranged to operate against the welted margin of the upper, means for holding the upper in said predetermined heightwise position comprising an inner upper-engaging plate and means constructed and arranged to act against the outer surface of the upper to grip the upper

against said plate, and means for shaping the upper while it is so held.

32. In a machine for shaping prewelt uppers, means for yieldingly supporting an inverted prewelt upper, means operating against the welted margin of the upper to locate the upper in a predetermined heightwise position, inner and outer upper-engaging forms constructed and arranged to grip the upper and hold it in its predetermined heightwise position, and means for shaping the upper while it is so held.

33. In a machine for shaping prewelt uppers, means for yieldingly supporting an inverted prewelt upper by engagement within the welt crease, means constructed and arranged to engage the welted margin of the upper thereby to locate the upper in a predetermined heightwise position relatively to the operating instrumentalities of the machine, inner and outer upper-shaping forms constructed and arranged to engage the upper along a line adjacent to the overwiping margin and to hold the upper in said predetermined heightwise position, and means for wiping the upper margin in over said inner form.

34. In a machine for shaping prewelt uppers, means for yieldingly supporting a prewelt upper by its welted margin, an inner upper-shaping plate, an upper-positioning member constructed and arranged to engage the welted margin of the upper and to locate the upper in predetermined heightwise position relatively to said plate and also to bring the welted margin into a position of registration with the edge face of said plate, and means for wiping the welted margin in over said plate.

35. In a machine for shaping prewelt uppers, means for yieldingly supporting a prewelt upper by its welted margin, an inner upper-shaping plate, an upper-positioning member constructed and arranged to engage the welted margin of the upper and to locate the upper in predetermined heightwise position relatively to said plate and also to bring the welted margin into a position of registration with the edge face of said plate, outer forms constructed and arranged to cooperate with said inner upper-shaping plate to grip and hold the upper in said predetermined heightwise position, and means for wiping the welted margin in over said plate.

36. In a machine for shaping prewelt uppers, means for yieldingly supporting a prewelt upper by its welted margin, an inner upper-shaping plate, an upper-positioning member constructed and arranged to engage the welted margin of the upper and to position the upper heightwise thereof in predetermined relation to said plate and also to position the welted margin to register with the edge face of said plate, a pair of outer upper-shaping forms, the upper-engaging surfaces of which are complementary in shape to the upper-engaging surface of said inner upper-shaping plate, said forms being constructed and arranged to grip the upper between them and to hold the upper in said predetermined heightwise position, and means for wiping the welted margin in over said plate.

37. In an upper-shaping machine, an upper-engaging member constructed and arranged to locate an upper in predetermined heightwise position in the machine, an inner upper-engaging member operable to grip the upper against cooperating gripping means and to hold the upper in said predetermined heightwise position, and means for shaping the upper while it is so held.

38. In an upper-shaping machine, an upper-

Engaging member constructed and arranged to locate an upper in a predetermined heightwise position, means for holding the upper in said position comprising an inner upper-engaging member and outer forms constructed and arranged to cooperate with said inner upper-engaging member, and a wiper for wiping the bottom margin of the upper in over said member.

39. In an upper-shaping machine, an upper-engaging member constructed and arranged to locate an upper in predetermined heightwise position, outer upper-engaging forms, an inner upper-engaging plate operable to grip the upper against said forms and to hold it in said predetermined heightwise position, means for locking said plate in upper-gripping position, and means for shaping the upper while it is so held.

40. In an upper-shaping machine, an upper-engaging member constructed and arranged to locate an upper in predetermined heightwise position, outer upper-engaging forms, an inner upper-engaging plate operable to grip the upper against said forms and to hold it in said predetermined heightwise position, means for locking said plate in upper-gripping position, means for wiping the bottom margin of the upper in over said plate, and means for retracting said upper-engaging member to provide clearance for the wiping operation.

41. In an upper-shaping machine, an upper-engaging member constructed and arranged to locate the lower marginal portion of an upper in a predetermined heightwise position, outer upper-engaging forms, an inner upper-engaging form constructed and arranged to cooperate with said outer forms to grip the said marginal portion and hold it in said predetermined heightwise position, an actuator for advancing said upper-engaging member and said inner form and for retracting said upper-engaging member while the inner form remains in its advanced position, locking means for holding said inner form in its advanced or upper-gripping position, and means for wiping said marginal portion of the upper in over said inner form.

42. In an upper-shaping machine, an upper-engaging plate constructed and arranged to engage the bottom margin of an upper and thereby to locate the upper in a predetermined heightwise position, means for gripping and holding the upper in said predetermined heightwise position comprising outer upper-engaging forms and a cooperating inner form, an actuator for advancing said upper-engaging plate, for bringing said inner form into upper-gripping position and for retracting said plate while said inner form remains in upper-gripping position, a detent for holding said inner form in upper-gripping position, and means for wiping the bottom margin of the upper in over said inner form while the upper is so gripped.

43. In an upper-shaping machine, means for gripping an upper along a line adjacent to its overwiping margin comprising inner and outer upper-engaging forms, a wiper for wiping the lasting margin in over said inner upper-engaging form and gripping it against said form, means for retracting said outer upper-engaging form after the upper has been gripped by the wiper, and means for expanding the upper.

44. In an upper-shaping machine, means for gripping an upper along a line adjacent to its overwiping margin comprising inner and outer upper-engaging forms, a wiper for wiping the lasting margin in over said inner upper-engag-

ing form and gripping it against said form, means for retracting said outer upper-engaging form after the upper has been gripped by the wiper, a common actuator for said wiper and said retracting means, and means for expanding the upper.

45. In an upper-shaping machine, means for gripping and holding an upper along a line adjacent to its overwiping margin comprising an inner upper-engaging plate and a pair of outer upper-engaging forms, a carrier on which said forms are mounted, means operating on said carrier yieldingly to retain said outer forms in upper-gripping position, means for laying the overlapping margin in over the margin of said inner upper-engaging plate and gripping said overwiping margin against said plate, an actuator for said wiping means, and means operated by said actuator after the wiping means has gripped the overwiping margin against said plate for retracting said outer forms to provide clearance for subsequent upper-shaping operations.

46. In an upper-shaping machine, means for gripping an upper along a line adjacent to its overwiping margin comprising inner and outer upper-engaging forms, a wiper for laying said overwiping margin in over the margin of said inner form and gripping the overwiped margin against said form, an inner mold movable lengthwise of the upper to bulge the upper, and means for retracting the outer form to provide clearance for the operation of said mold.

47. In an upper-shaping machine, means for gripping an upper along a line adjacent to its overwiping margin comprising inner and outer upper-engaging forms, a wiper for laying said overwiping margin in over the margin of said inner form and gripping the overwiped margin against said form, an inner mold movable lengthwise of the upper to bulge the upper, an actuator for said wiping means, and means operated by said actuator after the wiping means has gripped the overwiped margin against said inner form to retract said outer form thereby to provide clearance for the operation of said mold.

48. In a machine for shaping prewelt uppers, means including an inner upper-shaping plate for gripping and holding a prewelt upper along a line adjacent to its overwiping margin, a wiper constructed and arranged to wipe the welted margin in over said plate, and welt-conforming means constructed and arranged to engage the outer edge face of the welt and to bring the welt into predetermined relation to said inner upper-engaging plate for the wiping operation.

49. In a machine for shaping prewelt uppers, means including an inner upper-shaping plate for gripping a prewelt upper along a line adjacent to its welted margin, a wiper constructed and arranged to engage the sole-attaching face of the welt and to bend the welt into sole-attaching position and thereafter to lay the welted margin against said inner upper-engaging plate, and means operable after the welt-bending operation of the wiper and before the wiper operates to lay the welted margin in over said inner upper-engaging plate to engage the outer edge face of the welt thereby to position the welted margin in predetermined relation to said plate for the overlaying operation of the wiper.

50. In a machine for shaping prewelt uppers, means including an inner upper-shaping plate for gripping and holding a prewelt upper along a line adjacent to its overwiping margin, a wiper constructed and arranged to wipe the welted

margin in over said plate, welt-conforming means constructed and arranged to engage the outer edge face of the welt and to bring the welt into predetermined relation to said inner upper-engaging plate, and a carrier on which both the wiper and the welt-conforming means are mounted.

51. In a machine for shaping prewelt uppers, means including an inner upper-shaping plate for gripping a prewelt upper along a line adjacent to its welted margin, a wiper for bending the welted margin over said plate into sole-attaching position, a wiper carrier, a welt-conforming plate mounted on said carrier and arranged to engage the outer edge face of the welt to position the welted margin of the upper in predetermined relation to said inner upper-engaging plate and to hold the welted margin in said position while the wiper advances relatively to said welt-conforming plate to lay the welted margin upon said inner upper-engaging plate.

52. In an upper-shaping machine, an inner form the edge face of which defines a line corresponding generally to the peripheral contour of an end portion of a shoe bottom, a wiper member for wiping the bottom margin of an upper in over the margin of the inner form, means for applying wiping pressure to the wiper member, means for applying gripping pressure to the wiper member upon the completion of the wiping operation, and means for expanding the upper.

53. In an upper-shaping machine, an inner form the edge face of which defines a line corresponding generally to the peripheral contour of an end portion of a shoe bottom, a wiper member for wiping the bottom margin of an upper in over the margin of the inner form, a presser member for applying wiping pressure to said wiper member, and a presser bar for applying upper-gripping pressure to said wiper member.

54. In a machine for shaping prewelt uppers, an inner form, means for turning the welted margin of the upper inwardly over the margin of said form, and means constructed and arranged to engage the outer edge face of the welt and to position the welt in predetermined relation to the margin of the inner form.

55. In a machine for shaping prewelt uppers, an inner form constructed and arranged to receive the welted margin of a prewelt upper in overwiped position, means for wiping the welted margin in over the margin of said form, and means constructed and arranged to engage the outer edge face of the welt and to position said outer edge face uniformly distant from the edge face of said form.

56. In a machine for shaping prewelt uppers, a plate constructed and arranged to enter an end portion of a supported prewelt upper, a wiper operable to lay the welted margin inwardly over the margin of said plate, and means for positioning the welted margin relatively to said plate comprising a member having a welt-engaging surface defining a predetermined position of the outer edge face of the welt with relation to said plate.

57. In a machine for shaping prewelt uppers, an inner plate having a flat surface for receiving the welted margin of a prewelt upper in overwiped position, a wiper constructed and arranged to operate against the sole-attaching face of the welt, and a welt-positioning plate constructed and arranged to engage the outer edge face of the welt and to position it in predetermined relation to the edge face of said inner plate.

58. In an upper-shaping machine, an inner upper-shaping plate, a wiper for wiping the bottom margin of an upper in over said plate, means for applying pressure to the wiper to grip the overwiped margin against said plate, a common actuator for said wiper and said pressure-applying means, and connections between said actuator and the wiper constructed and arranged to enable the actuator to operate the pressure-applying means after the wiper has come to rest.

59. In an upper-shaping machine, an inner upper-shaping plate, a wiper for wiping the bottom margin of an upper in over said plate, means for applying pressure to the wiper to cause the overwiped margin to be gripped between the wiper and said plate, a common actuator for the wiper and said pressure-applying means, toggle mechanism connecting the actuator to said wiper, and means operating after the wiper has come to rest to cause the actuator to operate said toggle mechanism idly and to operate said pressure-applying mechanism.

60. In an upper-shaping machine, an inner upper-shaping plate, a wiper for wiping the bottom margin of an upper in over said plate, means for applying pressure to the wiper to grip the overwiped margin between the wiper and said plate, said means comprising presser members movable lengthwise of the upper relatively to said wiper, means for applying pressure heightwise of the upper to said presser members, and means for expanding the overwiped upper.

61. In an upper-shaping machine, an inner upper-shaping plate, a wiper for wiping the bottom margin of an upper in over said plate, means for applying pressure to the wiper to grip the overwiped margin between the wiper and said plate, said means comprising presser members movable lengthwise of the upper relatively to said wiper, and spring-pressed rolls constructed and arranged to act against said presser members to cause them to apply pressure heightwise of the upper to the wiper.

62. In a machine for shaping prewelt uppers, means for yieldingly supporting an inverted prewelt upper by engagement within the welt crease, inner and outer forms for gripping and holding the supported upper, a wiper for wiping the welted margin in over said inner form, and means actuated by the advancement of said wiper for retracting said upper supporting means out of the path of movement of the wiper.

63. In an upper-shaping machine, an inner upper-engaging plate, a wiper for wiping the bottom margin of an upper in over said plate, means for applying wiping pressure to said wiper during its wiping operation, means for applying gripping pressure to said wiper upon the completion of its wiping operation, and means for molding the upper while the overwiped margin is gripped between the wiper and the plate.

64. In an upper-shaping machine, an inner upper-engaging plate, a wiper for wiping the bottom margin of an upper in over said plate, presser bars carried by said wiper, means operating during the overwiping movement of said wiper to cause the wiper to apply overwiping pressure to the upper, means operated by movement of said presser bars relatively to the wiper upon completion of the overwiping operation to cause said wiper to apply gripping pressure to the overwiped margin to grip it against said inner upper-engaging plate, and means for molding the upper while it is gripped between the wiper and said plate.

65. In an upper-shaping machine, an inner upper-shaping member, a wiper for wiping the bottom margin of an upper in over said upper-shaping member, an operating member constructed and arranged to advance and to retract said wiper, an actuator, and connections through which said actuator, by repeated movements in a given direction, operates alternately to advance and to retract said operating member.

66. In an upper-shaping machine, an inner upper-shaping member, a wiper for wiping the bottom margin of an upper in over said member, an operating member for advancing and retracting said wiper, an actuator, a link through which said actuator advances said operating member, another link through which said actuator retracts said operating member, and means for rendering said links interchangeably operative and inoperative.

67. In an upper-shaping machine, an inner upper-shaping member, a wiper for wiping the bottom margin of an upper in over said member, an operating member for advancing and retracting said wiper, a hook operable to advance said operating member, another hook operable to retract said operating member, and means for moving said hooks so that first one and then the other is in operative position.

68. In an upper-shaping machine, an inner upper-shaping member, a wiper for wiping the bottom margin of an upper in over said member, an operating member for advancing and retracting said wiper, a hook operable to advance said operating member, another hook operable to retract said operating member, means for transferring said hooks so that first one and then the other is in operative position, and an actuator for operating said hooks and said transferring means.

69. In an upper-shaping machine, an inner upper-shaping member, a wiper for wiping the bottom margin of an upper in over said upper-shaping member, an operating member for alternately advancing and retracting said wiper, a rocker connected to said operating member, an actuator, means connecting said actuator to the opposite ends of said rocker, respectively, and means for rendering the connecting means from the actuator to said rocker alternately effective and ineffective.

70. In a machine for shaping prewelt uppers, an inner upper-engaging plate, a wiper constructed and arranged to operate against the sole-attaching face of the welt of a prewelt upper, said wiper being mounted to advance into welt-engaging position along a line having an inclination to the wiping plane thereby to facilitate the bending of the welted margin of the upper into sole-attaching position.

71. In a machine for shaping prewelt uppers, an inner upper-shaping plate, a wiper constructed and arranged to operate against the sole-attaching face of the welt of a prewelt upper, means for supporting the wiper in a position inclined relatively to the wiping plane during its advancement into welt-engaging position, thus to facilitate the bending of the welted margin into its sole-attaching position.

72. In a machine for shaping prewelt uppers, an inner upper-shaping plate, a wiper constructed and arranged to operate against the sole-attaching face of the welt of a prewelt upper to wipe the welted margin in over said plate, means for supporting the wiper in a position inclined relatively to the wiping plane during its ad-

vancement into welt-engaging position, thus to facilitate the bending of the welted margin into its sole-attaching position, said supporting means being so positioned relatively to the supported upper that the wiper is lifted from said supporting means as it advances upon the welt to perform the overwiping operation and is thereafter positioned heightwise of the upper solely by its engagement with the welt.

10 73. In an upper-shaping machine, an upper-shaping expander comprising an inner upper-shaping plate and an inner upper-shaping mold, means against which said plate grips a supported upper, means for actuating said expander to bring said plate into gripping engagement with the upper, and means for actuating said expander to expand and shape the upper.

20 74. In an upper-shaping machine, means constructed and arranged to engage the bottom edge of a supported upper thereby to position the upper heightwise thereof in the machine, an upper-shaping expander comprising an inner upper-shaping plate and an inner upper-shaping mold, a member against which said plate grips the supported upper, an actuator for operating said upper-positioning means and for advancing the expander to bring said plate into upper-gripping position and another actuator for operating said expander to expand and shape the upper.

25 75. In an upper-shaping machine, an upper-positioning member movable heightwise of a supported upper into engagement with its bottom edge to locate the upper heightwise thereof in the machine, an inner upper-shaping plate, an outer form against which said plate grips the upper after the upper has been located by said positioning member, and an actuator for first operating said upper-positioning member and for thereafter operating said plate to grip the upper

30 10 against said outer form.

76. In an upper-shaping machine, an upper-positioning member constructed and arranged to engage the bottom edge of a supported upper and to locate the upper in predetermined heightwise position in the machine, an inner upper-shaping plate, a pair of outer upper-shaping forms constructed and arranged to cooperate with said plate to grip and hold the upper in predetermined heightwise position, and an actuator

35 50 for first operating said upper-positioning member and thereafter advancing said plate into upper-gripping position.

77. In an upper-shaping machine, an upper-shaping expander comprising an inner upper-shaping plate and an upper shaping mold, an actuator, means on which said actuator operates to effect relative movement of said plate and said mold heightwise of a supported upper, and means through which said actuator operates to effect relative movement of said plate and said mold lengthwise of the upper.

78. In an upper-shaping machine, an upper-shaping expander comprising an inner upper-shaping plate and an upper-shaping mold, an actuator, means on which said actuator operates to effect relative movement of said plate and said mold heightwise of a supported upper, and means through which said actuator operates to effect relative movement of said plate and said mold lengthwise of the upper, said lengthwise and heightwise movements occurring simultaneously.

79. In an upper-shaping machine, an upper-shaping expander comprising an inner upper-shaping plate and an upper-shaping mold, a member to which said plate is secured, a mold

carrier mounted in said member for movement heightwise of a supported upper, said mold being mounted in its carrier for movement lengthwise of the upper, an actuator constructed and arranged to move said mold carrier heightwise of the upper, and means operated by said actuator to move the mold lengthwise of the upper in its carrier.

80. In an upper-shaping machine, an upper-

shaping expander comprising an inner upper-shaping plate and an upper-shaping mold, a wiper for wiping the bottom margin of a supported upper in over said plate, a presser member for gripping the wiper against the overwiped margin of the upper, and an actuator for first operating said presser member and thereafter operating said mold to expand the upper.

ERIC A. HOLMGREN.

CERTIFICATE OF CORRECTION.

Patent No. 2,359,762.

October 10, 1944.

ERIC A. HOLMGREN.

It is hereby certified that error appears in the printed specification of the above numbered patent requiring correction as follows: Page 2, first column, line 45, for "upper-shaking" read --upper-shaping--; and second column, line 23, for "upper-extending" read --upper-expanding--; line 33, for "tie" read --toe--; page 5, second column, line 22-23, for "overwiper" read --overwiped--; line 70, for "connected" read --connect--; page 9, first column, line 35, claim 12, for "forepast" read --forepart--; page 11, second column, line 14, claim 45, for "overlapping" read --overwiping--; page 12, first column, line 55, claim 55, for "outed" read --outer--; and that the said Letters Patent should be read with this correction therein that the same may conform to the record of the case in the Patent Office.

Signed and sealed this 30th day of January, A. D. 1945.

Leslie Frazer
